UNITED STATES PATENT OFFICE.

JOHN JAY HANNAHS, OF NEW YORK, AND ANTHONY A. HIEBER, OF BROOKLYN, NEW YORK, ASSIGNORS, BY DIRECT AND MESNE ASSIGNMENTS, TO UNIVERSAL TYPEWRITER COMPANY, A CORPORATION OF NEW YORK.

TYPE-WRITING MACHINE.

No. 849,127.

Specification of Letters Patent.

Patented April 2, 1907.

Application filed February 4, 1901. Serial No. 45,810.

To all whom it may concern:

Be it known that we, JOHN JAY HANNAHS, residing at 210 West Fourth street, New York, county of New York, State of New York, and ANTHONY A. HIEBER, residing at 1243 Putnam avenue, Brooklyn, county of Kings, State of New York, both citizens of the United States, have invented certain new and useful Improvements in Type-Writing Machines, fully described and represented in the following specification and the accompanying drawings, forming a part of the same.

The object of the present invention is primarily to furnish an improved means of operating a type-bar with a head having a plurality of type-faces whereby the key connected with such type-bar may be used to print a capital or small letter as well as a number or other character. To effect this result, we form the heads of the type-bars having each a plurality of characters thereon transverse to the type-bars, so that the several characters may be brought to the printing-plane by merely inclining the pivot-shaft of the bar above or below a horizontal line. To make all the impressions at the same printing-point, we shift the bearings of the pivot-shafts at an inclination to a vertical plane, and thus enable the several characters to strike the printing-point.

An alinement-guide is provided at the printing-point and is preferably formed with parallel cheeks, between which the head of the type-bar strikes, and the guide is furnished with one or more teeth and the head with one or more notches (or vice versa) to set each character accurately over the printing-point in the different adjustments of the head. To expose the printing-point to view, a shifting ribbon-guide is provided to guide the ribbon across the printing-point, and to increase the capacity of the machine and at the same time leave the printing-point fully exposed to the view of the operator the type-bars are mounted in two groups at opposite sides of the alinement-guide, and their pivot-shafts are so journaled as to swing them across the line of vision toward such guide. The type-bars in each group have their pivot-shafts journaled in a triangular frame called the "journal-plate" herein.

To direct the type-faces carried by each type-bar toward the printing-point when required, one end of each journal-plate is movable transversely to the line of writing and is actuated at pleasure by two shift-keys which operate, respectively, to shift such end of the plate outwardly or inwardly to bring the lower or inner end of the type-bar head over the printing-point. Such shifting of the journal-plate, which directs to the same printing-point the various characters upon the head of the type-bar, takes the place in the present invention of the carriage-shifting device or platen-shifting device heretofore used for enabling each of the characters upon the type-bar to make its impression separately.

In the drawings the invention is illustrated in connection with a flat platen supporting the base-frame of the machine, upon which the carriage is adjustable for line-spacing, and it is obvious that a plurality of characters or type-faces cannot be placed upon the same plane on the head of the type-bar where such type-faces are impressed upon a flat platen, as all would make impressions simultaneously.

To adapt such a construction of type-bar and such shifting device as we have described for use with a flat platen, we form the adjacent type-faces in planes inclined to one another upon the head of the type-bar and provide means for rocking or tilting the journal-plate upon which the pivot-shafts of the type-bars are journaled, so as to bring the several type-faces parallel with the printing plane at pleasure. With such means for rocking or tilting the journal-plate a flat platen can be used in connection with a keyboard having a moderate number of keys and three times as many characters (three upon each head) can be printed as the number of keys.

The invention includes various details of construction for carrying into operation the above-described improvements, all of which will be understood by reference to the annexed drawings, in which—

Figure 1 is a plan of a machine with the base-frame adapted to set upon a platen. Fig. 1^a is a section of the letter-adjusting device. Fig. 2 shows the under side of the bed and type mechanism. Fig. 3 is an end ele-

vation of the machine with the base-frame and platen. Fig. 4 is a diagram showing the outer and inner adjustment of the journal-plate and the corresponding engagements of the type-bar heads with the alinement-guide. Fig. 5 is a plan of one half of the devices for shifting and locking the journal-plate, the remaining half of the bed-frame and such devices being omitted for want of room and various parts broken away to exhibit the locking devices. The upright post which is shown in Fig. 6 carrying the stops *r* is omitted from Fig. 5 to clearly show the pivotal connection of the swivel-box *o* with the bed *a*. Fig. 6 is an end elevation of the shifting and locking devices with the two shifting-keys and their levers, the nearer post for the fulcrum-bar of the key-levers being broken away and the bed-frame shown in section upon line *xx* in Fig. 5, thus exposing to view the journal-plate, which is not shown in Fig. 5, as well as the gage-arm and stops for such journal-plate. Fig. 7 is an end elevation of the parts shown in Fig. 6 with the outer shift-key depressed. Fig. 8 is a plan of the line-feed devices with the feed-arm and feed-lever separated. Fig. 9 is a plan of the same with the feed-arm and feed-lever engaged by the catch. Fig. 10 is a plan of the guide for the shifting box of the journal-plate. Fig. 11 is an elevation at the outer end of the same. Fig. 12 is an elevation of the inner side of the same. Fig. 13 is a cross-section on line 13-13 in Fig. 1, showing only a part of the base-frame and platen. Fig. 14 is an elevation of the inner edge of the journal-plate with two of the pivot-shaft cranks and one of the key-levers and its connections, and Fig. 15 is a view of the joint-piece (from one of the connections) removed from the crank and adjusting-socket. Figs. 16 and 17 are diagrams showing the effect of the rocking and shifting devices in bringing the lateral type-faces upon the head of each type-bar to the printing-point and simultaneously inclining the head to set such lateral face parallel with the printing plane. Fig. 18 is an elevation of the dog 63 and the trip 64, and Fig. 19 is a plan of the rack 52 with the dog 63 thereon.

a designates the bed supporting the type mechanism and having the alinement-guide *b* fixed in its center adjacent to the printing-point *b'*. The ribbon-guide *d* is movable on the shank of the alinement-guide and is advanced over the printing-point in the usual manner at each downward impression of a type-bar. A fulcrum-plate *f* is mounted on posts *g* and *h* at each side of the center, and key-levers *i* are fitted thereto and held in place by slots in a bar *j*. (See Fig. 13.)

The finger-keys are connected by cranks *e* with pivot-shanks *k*, journaled in bearings upon the journal-plate *m*. Each so-called "journal-plate" is made, for convenience, of a

triangular frame with its outer end jointed by pivot *6* upon a swivel-box *o* and its inner end jointed by pivot *8* upon a shifting box *p*, and the end of the frame next the swivel-box *o* is provided with a gage-arm *q*, which is movable between stops *r* and is employed to rock the journal-plate in opposite directions, as indicated in full and dotted lines in Fig. 7. A post is shown in Fig. 6, as well as in Fig. 1, projected from opposite ends of the bed *a* for carrying the stops *r*.

Each of the type-bars *s* is formed with a transverse head *t* bearing three characters whose type-faces lie upon different planes, as shown in Figs. 1 and 5. The head extends approximately into parallelism with the pivot-shaft of its type-bar, so that a plane can be extended approximately through the pivot-shaft and the head whatever the position of the type-bar, and the head is extended from one side of the bar, so that it may not interfere with the arrangement of the bars (upon a common journal-plate) so as to move past one another to the printing-point.

The pivot-shafts *k* of the type-bars are journaled in the journal-plate at graduated distances from the printing-point, and the type-bars are of corresponding lengths.

The ends *l* of the bearings (when the journal-plate is in its normal position) project progressively, as shown in Fig. 5, upon the rear edge of the journal-plate, with the faces of the bearings all tangential to a common tangent curve *n* drawn about the printing-point. This arrangement brings the axes of the various pivot-shafts on which the type-bars are supported into substantial, though not absolute, parallelism with one another. This relation is an important one, as it enables the type-heads to be of substantially uniform length, form, and arrangement and at the same time to be capable of printing operatively with type-faces in different planes when the supporting-frame of the various pivot-shafts is rocked. The bearings in the journal-plate are at right angles to the faces *l* and are of gradually-increasing lengths from the inner to the outer end of the journal-plate. By making the journal-plate with converging sides or edges its front edge *l'* may be set parallel with the fulcrum-plate *f*, while the type-bars move at different angles from its rear edge to reach the printing-point.

The pivots 6 and 8 are, as shown in Fig. 4, set upon lugs projected beyond the edge *l'*, and the cranks *e* are arranged in a right line between the pivots and adapted to oscillate above and below such line, as shown in Fig. 14. This construction maintains the relation of the cranks to the key-lever connections when the journal-plate is rocked on the said pivots. The line of the pivots and cranks is preferably made, as shown in Fig. 1, parallel with the fulcrum-plate *f*, so that the

key-levers *i* make uniform connections with the cranks *e*. Such connections are made by an adjusting-socket *w*, hinged upon the key-lever *i*, and a joint-piece *y*, threaded into such socket and having a crank-pin at right angles to its bottom end to fit the eye of the crank *e*, (see Fig. 14,) and a spring *z*, which presses normally upon the end of the crank-pin to hold it normally in the eye. Such construction furnishes a quickly-detachable connection and facilitates the assembling of the parts and repairs to the machine. The journal-plate is shown with a central opening, forming bars on its converging sides, in which two opposite bearings are made for each of the pivot-shafts. A series of bearings (with the bearings upon different lines) is thus formed across the journal-plate; but the pivot-shafts and their respective bearings are not strictly parallel with one another, (although so represented upon the small-scale view in Fig. 1,) because the tangent lines from the faces or ends *l* of the bearings are slightly inclined to one another. By the pivotal supports of the journal-plate its rocking movement changes the inclination of all the shafts, (to the horizontal plane,) while the shifting of the box *p* changes their inclination to a vertical plane. The journal-plate is in practice divided upon the line of the bearings, as shown in Fig. 14, and the lower part secured to the upper part by screws. The upper part is provided with the gage-arm *q* and the pivot connections with the boxes *o* and *p*.

35. A spring *l*, Fig. 13, holds the finger-keys and the type-bars normally raised, the heads *t* resting upon a cushion *2'* upon a head-rest *3'*, projected upward from the journal-plate. Each of the heads *t* is shown (see Fig. 16) with three characters having their type-faces inclined to one another, the lateral faces thus being raised above the paper or platen when the central face is printing. By shifting the inner end of the journal-plate toward the finger-keys, as shown at the left side of Fig. 4, the outer type-face is brought in line with the printing-point, and the rocking of the journal-plate downwardly, as shown in Fig. 7, brings such type-face parallel with the printing plane and raises the other two type-faces so as to clear the same when the outer character is being printed. The shifting of the inner end of the journal-plate outwardly, as shown at the right side of Fig. 4, produces the reverse effect upon the head of the type-bar and brings the opposite character in line with the printing-point, and the simultaneous rocking or tilting of the journal-plate in the opposite direction, as indicated in dotted lines in Fig. 7, brings the face of such character parallel with the paper and raises the other two characters above the same.

55. The shift-keys are marked in Fig. 1 respectively "Cap" and "Fig.," and the capitals and figures, with various other charac-

ters, are formed upon the heads of the type-bars upon their inclined faces, which faces are thrown, respectively, into line with the printing-point by depressing such keys.

The intermediate type-faces are employed for the small letters, punctuation, &c., and each of the keys has in practice three characters marked thereon, as is usual in machines where each key is employed to print more than one character.

To bring the characters central over the printing-point, the alinement-guide is provided with two opposite curved cheeks, adapted to receive the edges of the heads *t*, and one of the cheeks is provided with two teeth *c* and each of the heads *t* with notches upon one of its edges intermediate to the type-faces, which notches are adapted to fit either of the teeth *c*, and thus guide the character accurately into the printing position when the notches are shifted above or below the printing-point in different adjustments of the head. The curvature of the cheeks is clearly shown in Fig. 4, (where the letter *b* is applied to each of the cheeks,) and the head *t* of the left-hand type-bar *s* is shown inserted in dotted lines between the cheeks and the lower end of the head curved away from the right-hand cheek. The heads of all the type-bars are made with the same curvature, and the type upon the heads are in a corresponding curved line, so that all of the type on the separate type-faces may be brought in succession to the same printing-point by swinging the support of the type-bar upon the swivel-box *o*. The inner faces of the cheeks and of the teeth *c* are tapered upwardly to easily receive the notched head of the type-bar and to direct it gradually into the correct position. (See Fig. 14.)

40. The shifting box *p*, upon which the inner end of each of the journal-plates is pivoted, is automatically locked when in its central position by dogs *34*, fitted, respectively, to the inner and outer faces of a stud *2* upon the shifting box, and each of the shift-keys when depressed operates upon a locking-arm *5*, which lifts one of the dogs, and upon a rocker-arm *9*, which through suitable connections *11 12* slides the shifting box into its intended position and simultaneously rocks the journal-plate by a connection *37* with the gage-arm *q*.

45. A crank-pin *10* is projected laterally from the top of the rocker-arm *9* (see Fig. 5) to oscillate such arm, and the top of the locking-arm *5* is provided, as shown in Fig. 7, with two beveled faces to actuate such arm. The lever *18* for the shift-key marked "Cap" crosses the crank-pin *10* and the doubly-inclined head of the locking-lever *5* and is provided with an inclined slot *20*, which operates to shift the rocking lever to the left, as shown in Fig. 7, the upper end only of the lever being designated, (by dotted lines,) to

55. The shift-keys are marked in Fig. 1 respectively "Cap" and "Fig.," and the capitals and figures, with various other charac-

avoid confusing the parts nearer to the shaft 13, to which such rocking lever is rigidly attached.

The rocking arm 9 is attached to the shaft 13, (see Fig. 7,) and two cranks 12 are attached to such shaft, from which cranks two sets of the connections 11 extend to the two shifting boxes *p*. (See Fig. 1.)

The shifting box is held in place upon the bed *a* by a yoke 14, (see Figs. 10 to 12,) which projects over the box and serves as stops for the sides of the stud 2. A screw 15 is shown to vary the stroke of the shifting box, and such screws may be placed in both ends of the 15 yoke, if desired.

The dogs 3 4 consist of arms pivoted loosely on the shaft 13. One of the dogs 4 is provided for each of the shifting boxes *p*, and both of such dogs 4 are tied together by a bar 20 16. The two dogs 3 are tied together by a similar bar 17, which is arched over the dogs 4 sufficiently to let them lift when the dogs 3 are depressed. The locking-arm 5 operates upon the dogs 3 4, which are nearest to the 25 shifting-keys, and such dogs raise the opposite ones to which they are tied by the bars 16 and 17, so as to lock or release both of the shifting boxes simultaneously.

The shift-lever 18 is provided with a jaw 21, 30 the lower end of which jaw strikes one of the inclined faces upon the locking-lever 5 and moves it to the right, as shown in Fig. 7. Such movement lifts the dog 3 into the position shown in Fig. 7 and holds it in such position during the shifting of the rocker-arm, which moves the shifting box *p*. The locking-lever as it turns loosely upon the shaft turns an arm 22, to which it is tied by a bar 23, (see Fig. 5,) and the arm 22 has a finger 40 22^a, which projects under the dog 3 and operates to lift such dog, as shown in Fig. 7, when actuated by the shift-key marked "Cap." The dog 3 is notched upon its under side near its connection with the shaft 13, and a double-45 armed lever 24 is pivoted beneath the arm 22 (between such arm and the dog 3) and provided with a pin 25, which extends through such notch and underneath the dog 4. The shift-lever 26 of the key marked "Fig." is 50 provided also with a slot 20 and a jaw 21, which are so shaped that they produce when operated upon the locking-lever, and the rocking lever movements in a reverse direction from those produced by the slot and jaw upon the shift-lever 18, and when the shift-lever 18 is raised and the shift-lever 26 depressed the rocking arm is moved to the right and the locking-arm is moved to the 55 left, as viewed in Fig. 7. Such movement depresses the finger 22^a against the outer end of the lever 24 and raises the pin 25 upon its inner end, so as to lift the dog 4 without disturbing the dog 3. The shift-levers thus actuate the dogs in their first downward movement and then move the rocking lever 9,

which directly oscillates the journal-plate and indirectly moves the shifting box *p* through crank 12. Each of the shift-keys is connected with a pawl 27, which may be forced under the end of the guide-bar *j* at 70 pleasure to secure the journal-plate in either of its inclined positions, and thus print exclusively the characters upon one of the inclined type-faces.

The shifting box is shown in its central position in Fig. 6, with the pivot 8 in the same vertical plane as the pivot 6, and the stud 2 locked in such position by both of the dogs 3 and 4. A dotted line A A is shown in Fig. 4, which passes through the printing-point 80 and the outer pivots 6, on which the journal-plates rock on the swivel-boxes *o*.

Each swivel-box is mounted upon a pin 7, on which it swivels when the journal-frame is shifted, as shown in Fig. 5. The line A A 85 extends through the pivot 8 of each shifting box when the latter is in the central position, as in Figs. 5 and 6; but Fig. 7 shows the box *p* shifted inwardly and the pivot 8 moved to one side of the pivot 6, the same as at the left side of Fig. 4.

Figs. 16 and 17 show the head of the type-bar with its right-hand and left-hand ends, respectively, tilted downward to bring the outer type-faces parallel with the printing 95 plane, the printing-point being indicated by the dotted line B B. It is immaterial what ribbon-feeding devices are used, and ribbon-spools with the ribbon extended between them are therefore indicated merely in 100 dotted lines in Fig. 2.

It will be noted that the type-bars are grouped in two nests, one at each side of the printing-center, the type-bars in each nest being mounted in a row which radiates from 105 the printing-center, as may be understood from Figs. 1, 3, and 4. The type-bars are of graduated lengths and pivoted at correspondingly-graduated distances from the printing-center, the shortest bar being closest 110 to the printing-center, the next longer bar adjoining the shortest, but being pivoted at a point more from the printing-center, and so on throughout each nest. The type-bars shown are of the single-arm variety, and it 115 will be understood that if these should be provided with parallel pivots the types upon the longest bars would have to be greatly offset from the bars, which is an objection, it being a desideratum in this class of machines 120 to have the types set as close as possible to the straight arm of the type-bar to conduce to stiffness of the structure. This result is obtained by mounting the pivots in converging relation, as seen plainly at Fig. 4, at the 125 right-hand side of which figure the pivot-bearings are shown in dotted lines in such relation, from which it will be noted that the pivots converge rearwardly and that the type upon even the longest bar is only slightly off- 130

set from the bar itself. It being necessary for the type-bars to swing past one another, they are arranged in echelon, as plainly seen at Fig. 13, and it follows that if the type-bar 5 pivots were parallel the types would lie in straight rows extending at right angles to the pivots, thus bringing the most remote type in each nest to a point where it would be a great distance from the main arm of its 10 type-bar, which objection is avoided by converging the type-bar pivots in a manner to cause the rows of types when in normal position to agree substantially with the directions in which the rows of type-bars are arranged, the type-rows, as well as the rows of type-bars, diverging rearwardly from the printing-point. When in printing position, the type-bars extend about radially from the printing-center to their pivots, as seen at Fig. 15 15 20 25 4, whereas if the pivots were parallel—that is, all having the same direction as the pivots of the innermost type-bars—the type-bars would all when in printing position lie parallel with the dotted line A, (seen at Fig. 4,) and hence the angular type-carrying arms would be unduly long on the more remote type-bars. This objection is avoided by converging the pivots, as shown.

Not only the bars, but also the types, are 30 arranged in echelon, as seen clearly at Fig. 3, and each row of type-bars radiates from the printing-center as distinguished from systems in which the type-bars are grouped in a circle or arc about the printing-center. 35 Each of the types is a multiple type—that is, is provided with two or more characters, one above the other, each type extending angularly from the end of the bar—and the type-faces upon each type are inclined to each 40 other, so that when one face is printing the others do not print.

The key-levers *i* are of the first order and mounted above the type-bar pivots and forwardly of the type-bars in place of extending 45 rearwardly beneath the type-bar system, as usual, the key-levers extending forwardly from the type-bars and links *w* depending from their rear ends to the type-bars or the operating-arms thereof. The system of levers is divided into two sets, the key-levers 50 of one set extending to the left-hand nest of type-bars and those of the other set extending to the right-hand nest, as at Fig. 1. Since the type-bar nests are separated, with 55 the printing-point between the nests, while the keys extend in unbroken rows across the machine, the two lever sets are made to diverge rearwardly from the keys to the type-bar nests. It is not intended in referring 60 herein to the divergence of the key-levers to mean that each lever diverges from the next, but that the two sets diverge, one set extending rearwardly and toward the left, while the other set extends rearwardly and toward the 65 right.

The type-bar pivots or rock-shafts *k*, Fig. 4, are of gradually-increasing lengths, beginning at the innermost one, and extend forwardly of the machine, the type-bars consequently striking down crosswise of the machine, the rock-shafts being provided with crank-arms *e* and the links *w* extending upwardly from said crank-arms to the key-levers. 70

The types upon all the bars have substantially uniform spacing and inclination—that is, the type-faces upon each bar have the same separation one from another and the same inclination one to another as the types upon all the other bars. The types are 80 shifted independently of the type-operating keys to enable the different types to print. During the rocking of the type-bar system by the shift-keys the links *w* vibrate about their points of connection to the key-levers, 85 the latter remaining stationary, the parts being jointed with sufficient looseness or play for this purpose.

The key-levers are mounted upon the frame or bed *a*, while the type-bars are pivoted upon frames *m*, mounted to rock upon said frame *a* independently of the key-levers *i*. One rocking-frame *m* is provided for each row of type-bars, and a key-controlled rock-shaft 13 connects said frames (by means of 90 rock-arms 9, links 37, and arms *q*) to cause the frames to rock together. Each frame is supported at its inner end for a compound pivotal and sliding motion, the shift-boxes *p* having the sliding motion and the frames being pivoted to said boxes, while at its outer end each frame is supported for a universal pivotal motion by means of the pivots 6 and 7, Fig. 5. The member *m* stands in normal 95 central position and is shiftable in either direction therefrom, the key 18 having a cam for shifting said member in one direction, the key 26 having a cam for shifting said member in the other direction, and the pair of dogs or locks 3 4 being normally effective for 100 locking said shiftable member against movement in either direction from normal central position, one of said locks being releasable by 105 the other of said keys, said locks being independently movable.

The alignment-guide comprises two jaws, between which the types fit upon a principle well known in this class of machines, the types being provided upon only one side with the guiding-notches and only one of said 110 jaws having teeth or projections *c* to fit into said notches. One of said projections fits the type-bar notches at one shift and the other fits the notches at the other shift.

Feeding to print on flat platen.—Figs. 1 and 125 13 show the bed *a*, provided at its rear edge with concavely-grooved rolls 40, fitted to a cylindrical guide-bar 41, which is sustained upon the rear bar 42 of the carriage. The bed can thus be turned upon or with the 130

guide-bar, while the rolls permit it to move longitudinally thereon.

The guide-bar is furnished with feed-rack, and the usual letter-spacing devices connect the rack with a spacing-key and universal lever, as is common. The side bars 43 of the carriage are fitted to the side bars 44 of a base-frame, which are connected by bars 44½ at the ends and fitted to rest upon or embrace a flat platen 70. (See Fig. 3.) The bars 44 are provided with rack-teeth to mesh in a feed-pinion 45, upon one or both of the carriage-bars 43. One pinion is shown in Fig. 1, and Figs. 8 and 9 show (enlarged) the construction of the feed-lever 46 and pawl connections to the pinion.

The feed-lever moves on the fulcrum of the pinion and has the pawl 47 formed with a heel-piece 48, adapted to strike a stop 49 upon the carriage when the lever is retracted, as shown in Fig. 8, the pressure of the stop upon the heel retracting the pawl from the pinion and leaving the pinion free to turn. An index 50 is attached to each side of the carriage in line with the printing-point, and where the printing is done on ruled paper the freedom of the pinion in such position of the pawl thus permits the setting of the carriage by the index, so as to print exactly upon any given line.

The feed mechanism is constructed especially to effect the line-feeding automatically each time the carriage is shifted to the left for writing upon another line. To effect such feeding automatically, the pawl 47 must be engaged with the pinion 45 during such shifting movement of the carriage, and to permit the carriage to be freely movable afterward (so as to set it more accurately by the aid of the index 50 or otherwise) the pawl must be detached from the pinion 45 at the end of the feeding movement. These joint relations of the parts are secured by providing a rack 52 movable upon the carriage and connecting it when required with the feed-lever 46 by a toothed arm 51, having a catch 57 to engage such feed-lever when the two parts are brought close together in the backward movement of the arm. The rack 52 has an adjustable dog 63 mounted thereon to engage a trip 64 upon the carriage. The trip is upon the middle of the carriage (see Figs. 1, 5, and 18) and yields when the carriage is feeding to the right for letter-spacing, but engages the dog 63 when shifted to the beginning of a line, and the dog is constructed to operate both as a feed-actuator and as a marginal stop for the carriage. The dog 63, Figs. 13, 18, and 19, is fitted to a slide upon the rack 52 and can be set at any point thereon by a spring-pawl 65. The catch 57 is engaged with a notch in the feed-lever 46, adjacent to the pawl 47, (when the feed-lever and the toothed arm are brought close together,) by a spring 'a', which serves normally to hold

the pawl 47 into the pinion 45 and indirectly to press upon the tailpiece of the catch and engage it with the feeding-lever, as shown in Fig. 9. When shifting the carriage to the left, the contact of the trip with the dog 63 operates to oscillate the toothed arm and (through the catch 57) to turn the feed-lever 46 with the pawl 47 in the teeth of the pinion 45, which is pressed into such teeth by its spring 'a' as soon as the heel of the pawl clears the stop 49 on the carriage.

To limit the feeding movement, an adjustable stop 56 is provided under the arm 51, and the tailpiece of the catch 57 forms a dog 55, which engages the pinion-teeth when pressed therein by the stop 56. When the dog presses into the pinion, the movement of the tailpiece withdraws the catch 57 from the notch in the feed-lever and the feed-lever is carried automatically back to its initial position (shown in Fig. 9) by a spring 66, attached to the arm 51. Such backward movement of the feed-lever throws the heel of the pawl 47 against the stop 49 on the carriage, and thus holds the pawl normally free from the pinion during the movement of the carriage as it feeds step by step for letter-spacing. The stop 56 is mounted upon a bell-crank, with a spring-arm 58 having a stud to engage a series of holes 59, which set the stop at various distances from the pawl, and thus determine the stroke permitted to the feed-lever, before the contact of the dog with the stop and with the teeth of the pinion, as shown in Fig. 8, operates to arrest the feed. The stop may be set to feed the pinion two, three, or four teeth by a single movement of the feed-lever. The stop operates to terminate the feeding movement and to lock the pinion 45 temporarily by throwing the dog 55 into the teeth of the pinion and arresting further movement of the toothed arm 51. This also operates to arrest the rack 52 and stops the reverse movement of the carriage to form the marginal stop, as described. A toothed arm 54 is journaled upon the opposite end of the carriage and connected with the arm 51 by the rack 52, so that a spring 53 (see left side of Fig. 1) may serve to return the arm 51 and the feed-lever to their initial position when the carriage is fed to the right during letter-spacing. This moves the arm 51 and carries the dog 55 clear of the pinion-teeth. Such return of the arm 51 to its initial position brings the catch 57 again into engagement with the feed-lever in readiness to actuate the pawl 46 anew when the carriage is again reversed. The feed-lever may be operated at any time by hand to turn the pinion one, two, or more teeth or for any small space required to set the index 50 to a given point or line upon the paper.

The feed mechanism is not claimed herein, and for this reason the toothed arm 54 (shown

at the left side of Fig. 1) is not fully illustrated. The means for bringing different type-faces upon the head of the type-bar to the same printing-point and the means for bringing inclined type-faces parallel with the printing-plane may be used upon a book type-writer or upon a type-writer intended for general work. To show their application to a round platen, one is indicated by 5 dotted lines 62 in Fig. 13 with one of the type-bars pressed thereon. The head of the type-bar is shown with three characters with their type-faces upon the same plane, (represented by the line C C.) It is obvious that 10 the type-faces may be arranged upon the same plane for printing upon a cylindrical platen, as each of the faces clears the curve of the platen when any of the others is printing, and the other devices described herein 15 20 25 may therefore be used to print upon a cylindrical platen by merely shifting one end of the fulcrum-plate, as already described, to bring any of the type-faces at pleasure to the printing-point and without the devices for rocking the fulcrum-plate.

From the above description it will be seen that the view of the printing is entirely unobstructed between the two sets of type-bars mounted upon the fulcrum-plate at opposite 30 sides of the printing-point, and as the bed *a* is hinged upon the guide-bar 41 by the rolls 40 the bed and type mechanism may obviously be lifted to make corrections in the printing whenever desired.

35 The position of the bed *a* upon the guide-bar 41 is determined by the letter-spacing devices, which engage the rack upon the guide-bar in the usual manner, and we have found it convenient to give the guide-bar a 40 small longitudinal adjustment equal in space to the width of a printed impression, so as to adjust the letters longitudinally upon the line of printing. Such adjustment is very 45 convenient where a page of printed matter has been removed from the machine and is reinstated to make corrections, as the index 50 enables the printed line to be set exactly under the printing-point, while the letter-adjustment described adjusts the printing-point in the alinement-guide *b* exactly over the point where the impression is desired. The letter-adjustment consists of a sleeve 60, journaled to turn without longitudinal movement in one of the bearings of the guide-bar 41, as shown in Fig. 1^a, and having two threads 61, between which a tooth 67, attached to the guide-bar, is fitted.

65 A handle 68 serves to turn the sleeve whenever required and by the pressure of the thread 61 upon the tooth 67 operates to move the guide-bar and the attached bed *a* in a small degree either to the right or the left, as may be required. We have not shown in detail any means of securing the paper upon the flat platen 70 (shown in Fig.

3) nor any means for connecting the carriage with the cylindrical platen 62, (shown in Fig. 13,) as such appliances form no part of the present invention.

It will be fully understood that the invention does not consist in the precise construction herein shown and described and that any equivalent form may be used for the respective elements, as is contemplated by the law, in case the precise form is not claimed. 70 75

The invention contemplates an alinement-guide at the printing-point, two series of type-bars having pivot-shafts journaled at opposite sides of the printing-point, and each type-bar having a head with a plurality of 80 type-faces disposed in planes inclined to one another and extended transversely from the type-bar, means for shifting the type-bar laterally to direct any of such type-faces to the printing-point, and means for twisting 85 the type-bar to set such type-faces at pleasure parallel with the platen to print thereon.

The projection of the type head transverse to the type-bar necessitates the shifting of the type-bar laterally and not longitudinally, 90 as in prior constructions, to bring the several type-faces to a fixed printing-point, and such disposition of the type-head also requires the twisting of the type-bar to bring the several type-faces into action, such twisting 95 in the construction shown herein being effected by rocking the journal-plate to vary the inclination (from the horizontal) of the pivot-shafts.

Having thus set forth the nature of the invention, what is claimed herein is—

1. In a type-writing machine, a pivoted frame, type-bars journaled therein and arranged to strike downwardly toward a printing-point, a plurality of types on each bar 105 having their faces inclined an appreciable amount with respect to one another so as to be incapable of printing simultaneously on a flat surface, and means for tilting said frame independently of the key-levers whereby the 110 different faces are made operative to strike the printing-point.

2. In a type-writing machine, a pivoted frame, type-bars journaled therein and having a plurality of type-faces inclined at an 115 appreciable angle to one another so as to be incapable of printing simultaneously on a flat surface, and means for tilting said frame independently of the key-levers to shift different type-faces into printable relation. 120

3. In a type-writer, a pivoted frame, type-bars journaled therein and each having three type-faces inclined at an appreciable angle with respect to one another so as to be incapable of printing simultaneously on a flat surface, and means whereby said frame is tilted independently of the key-levers to move different type-faces into striking relation to the printing-point. 125

4. In a type-writer, a flat platen and key- 130

levers, a frame, type-bars journaled therein, each having a plurality of type-faces inclined to one another, and means for tilting said frame independently of the key-levers where-
5 by any desired type-face may be brought into striking relation with a flat platen.

5. In a type-writing machine, the combination of a frame, key-operating levers mounted upon said frame, type-bars each 10 having type-heads substantially at right angles to the plane of movement thereof and having a plurality of types fixed thereon with the type-faces inclined an appreciable amount with respect to each other, and a rocking 15 frame also mounted upon said frame and carrying said type-bars, and movable independently of said key-levers.

6. In a type-writer, type-bars having at one end heads extended transversely to the bars and making substantially equal angles therewith, each having upon one side a plurality of type-faces, the faces being inclined an appreciable amount with respect to one another so as to be incapable of printing simultaneously upon a flat surface, and having at the other end a bearing transverse to the type-bar, and means for rocking the bar and its bearing to bring any desired type-face parallel with the printing-plane.

30 7. In a type-writer, a type-bar having at one end a pivot-shaft and at the other end a head extending transversely substantially at right angles to the bar and approximately in the plane of the shaft and having a plurality of type-faces inclined to one another so as to be incapable of printing simultaneously on a flat platen.

8. In a type-writer, the combination, with
a series of type-bars each having an independ-
ent pivot-shaft and means for rocking the
same and having a head with a plurality of
type-faces inclined to one another, of a jour-
nal-plate having bearings for the pivot-
shafts and means for shifting the journal
plate to bring the several type-faces to the
same printing-point.

9. In a type-writing machine, the combination of a system of type-bars, each having a plurality of types fixed thereon with the type
5c faces inclined an appreciable amount with respect to each other so as to be incapable of printing simultaneously on a flat surface, a system of key-levers for operating the type-bars, links extending from the levers to the
55 type-bars, and means for rocking the type-bar system to enable different types to print whereby the links vibrate about their points of connection to the key-levers during the rocking of the type-bar system.

60 10. In a type-writing machine, the combination of a system of type-bars, each having a plurality of types fixed thereon with the type-faces inclined an appreciable amount with respect to each other so as to be incapable of printing simultaneously on a flat sur-

face, a system of keys, a system of levers between the keys and the type-bars, and means for rocking said system of type-bars to enable the different types to print, while said key-levers remain stationary.

11. In a type-writing machine, the combination of a system of type-bars, the axes of which lie in two rows which radiate from opposite sides of the printing-point, each type-bar being provided with a plurality of types, 75 the types on each bar lying in appreciably different planes so as to be incapable of printing simultaneously on a flat surface, a system of key-operated levers for operating said type-bars, and means for shifting the type-bar system independently of the key-levers, to enable different types to print. 8c

12. In a type-writing machine, the combination with a system of type-bars, each having three types thereon with their faces inclined to one another a flat platen, and a system of keys for operating said type-bars, of means for rocking said system of type-bars in opposite directions from normal central position, independently of said keys, for enabling the different types to print. 85 90

13. In a type-writing machine, the combination with a system of type-bars, each having three types thereon with their faces inclined to one another so as to be incapable of printing simultaneously on a flat surface, said type-bars being pivoted in two rows which radiate from opposite sides of the printing-center, and a system of key-operated levers connected to said type-bars, of means for rocking said system of type-bars in opposite directions from normal central position while said levers are stationary, for enabling the different types to print. 95

14. In a type-writing machine, the combination of a flat platen, a system of type-bars, each having a plurality of types fixed thereon with the type-faces inclined to each other so as to be incapable of printing simultaneously on a flat surface, and the type-faces on all the bars having uniform spacing and inclination, of means for rocking the type system to enable the different types to print. 105 110

15. In a type-writing machine, the combination of a flat platen, a system of type-bars, each having three types fixed thereon with the type-faces inclined to each other so as to be incapable of printing simultaneously on a flat surface, the types on all the bars having uniform spacing and inclination, and means for rocking the type system in either direction from normal central position, to enable the extreme types to print. 115
120

16. In a type-writing machine, the combination of type-bars having the faces of their type arranged upon different planes, and a frame carrying the type-bars, pivotally carried upon a sliding support and adapted to be oscillated upon its pivot, with mechanism adapted to impart an oscillating motion to 125
130

the frame and a sliding movement to its support.

17. In a type-writer, the combination, with a series of type-bars each having a pivot-shaft and means for oscillating the same, and having a head with adjacent type-faces inclined to one another, of a journal-plate having bearings for the pivot-shafts, a fixed pivot at one end of the journal-plate, a movable pivot at the opposite end, and means for adjusting the movable pivot to bring the several type-faces to the same printing-point.

18. In a type-writer, the combination, with a series of type-bars each having a pivot-shaft and means for oscillating the same, and having a head with adjacent type-faces inclined to one another, of a journal-plate having bearings for the pivot-shafts, a fixed pivot at one end of the journal-plate, a movable pivot at the opposite end, means for locking the movable pivot in a central position, and means for unlocking the pivot and shifting it to lateral positions and locking it therein.

19. In a type-writer, the combination, with a series of type-bars each having a pivot-shaft and means for oscillating the same, and having a head with adjacent type-faces inclined to one another, of a journal-plate having bearings for the pivot-shafts, a fixed pivot at one end of the journal-plate, a movable pivot at the opposite end, means for locking the movable pivot in the central position, finger-keys for rocking the journal-plate into opposite positions, and connections from such keys for first unlocking the movable pivot, shifting the same, and relocking it when the journal-plate is shifted.

20. In a type-writer, the combination, with a series of type-bars each having a pivot-shaft and means for oscillating the same, and having a head with adjacent type-faces inclined to one another, of a journal-plate having bearings for the pivot-shafts, a fixed pivot at one end of the journal-plate, a movable pivot at the opposite end, means for locking the movable pivot in a central position, a locking-arm with rocker-arm attached, a shifting-lever to rock the journal-plate, a finger-key with lever having a slot engaged with such rocker-arm to first move the locking-arm and a slot engaged with the shifting-lever to rock the journal-plate, substantially as herein set forth.

21. In a type-writer, the combination, with an alinement-guide arranged over the printing-point and having a toothed cheek as set forth, of a pivot-shaft mounted at one side of such guide, a type-bar attached to such shaft and having a head extended transversely from the end of such bar approximately into the plane of said shaft, with adjacent type-faces inclined to one another upon the side of such head, and the head having notches in one edge to engage the teeth of the

alinement-guide, a movable bearing for the pivot-shaft, and means for shifting the bearing at an inclination to a vertical plane to direct the several type-faces to the printing-point.

22. In a type-writer, the combination, with an alinement-guide arranged over the printing-point, and having a toothed cheek as set forth, of opposed type-bars having pivot-shafts journaled in bearings at opposite sides of such alinement-guide, and provided with transverse heads having each a plurality of type-faces and notched upon one edge, the teeth in the alinement-guide arranged to engage the said notches in different adjustments of the head, and means for simultaneously shifting the bearings of the pivot-shafts at opposite sides of the alinement-guide to bring the corresponding type-faces upon such opposite type-bars, when operated, to the same printing-point.

23. In a type-writer, the combination, with a type-bar having a head with adjacent type-faces disposed in planes inclined to one another, and notches intermediate to the type-faces, of an alinement-guide arranged over the printing-point, and having a tooth to engage such notches in different adjustments of the said head, substantially as herein set forth.

24. In a type-writer, the combination, with a type-bar having a head with parallel edges and three type-faces disposed in planes inclined to one another, and notches upon the parallel edges intermediate to the type-faces, of an alinement-guide arranged over the printing-point and having cheeks to fit the edges of said head, and teeth above and below the printing-point to engage said notches in different adjustments of the head.

25. In a type-writer, the combination, with the triangular journal-plate *m* having opposed bearings in its converging sides, of a series of type-bars of gradually-increasing lengths having pivot-shafts fitted in the said opposite bearings, cranks at the rear ends of the type-bars and finger-keys with connections to the said cranks.

26. In a type-writer, the combination, with the triangular journal-plate *m* having opposed bearings in its converging sides, of a series of type-bars of gradually-increasing lengths having pivot-shafts fitted in the said opposite bearings, cranks at the rear ends of the type-bars, finger-keys with connections to the said cranks, and the type-bars having each a head with a plurality of type-faces inclined to one another and means for rocking the journal-plate to adjust the plane of each type-face to the printing-plane when in operation.

27. In a type-writer, the combination, with the triangular journal-plate *m* having opposed bearings in its converging sides, of a series of type-bars of gradually-increasing

lengths having pivot-shafts fitted in the said opposite bearings, cranks at the rear ends of the type-bars, finger-keys with connections to the said cranks, and the type-bars having each a head with a plurality of type-faces inclined to one another, means for rocking the journal-plate to adjust the plane of each type-face to the printing-plane, and means for shifting the journal-plate to bring the several type-faces to the same printing-point.

28. In a type-writer, the combination, with the triangular journal-plate *m* having opposed bearings in its converging sides, of a type-rest extended upwardly therefrom, a series of type-bars of gradually-increasing lengths having pivot-shafts fitted in the said opposite bearings, cranks upon the pivot-shafts, and finger-keys with connections to the said cranks to actuate the type-bars, substantially as herein set forth.

29. A type-writer having the two triangular journal-plates with their apices toward one another and an alinement-guide disposed between the same opposed bearings in the converging sides of the journal-plates, a series of type-bars with pivot-shafts fitted to the said opposite bearings, cranks upon the rear ends of the pivot-shafts and finger-keys with connections to said cranks, substantially as herein set forth.

30. A type-writer having the two triangular journal-plates with their apices toward one another and an alinement-guide disposed between the same, opposed bearings in the converging sides of the journal-plates, a series of type-bars having each a head with adjacent type-faces inclined toward one another, and a pivot-shaft fitted to opposed bearings in the journal-plate, cranks upon the pivot-shafts and finger-keys with connections to actuate the cranks, and means for rocking the journal-plate to bring the several type-faces parallel with the printing-plane when in operation.

31. In a type-writer, the combination, with a bed having an alinement-guide arranged at the printing-point, of a journal-plate having a series of bearings with their ends projected progressively upon one edge of the plate with the faces of the bearings all tangential to a common tangent curve at one side of the printing-point, a series of graduated type-bars extending from the projecting ends of such bearings tangentially to the said curve, and provided each with a transverse head adapted to extend across the printing-point, the several bearings upon the journal-plate being at right angles to the tangential faces of the bearings, and a head-rest being projected upward from the journal-plate, and the whole arranged and operated to support the heads upon the graduated bars normally one above the other when at rest, and to permit the heads to pass one over the other in moving to the printing-point.

32. In a type-writer, the combination, with a flat platen, a base-frame with a carriage having a bed and type mechanism movable thereon, and an alinement-guide at the printing-point within the bed, of two series of type-bars having pivot-shafts journaled at opposite sides of the printing-point and each type-bar having a head with a plurality of type-faces disposed in planes inclined to one another, means for directing any one of such type-faces to the printing-point and for rocking the head to set such type-faces at pleasure parallel with the platen.

33. In a type-writer, the combination, with the type-bar pivot-shaft and the crank *e* having an open eye at the end, of a key-lever and a link comprising a threaded socket pivoted upon the key-lever, a joint-piece screwed into the said socket with a lateral crank-pin at the end to engage the said eye, and a leaf-spring attached to the joint-piece and pressing normally upon the end of the crank-pin to retain it in the eye, whereby the link forms an adjustable and detachable connection with the crank.

34. In a type-writer, the combination, with a bed having an alinement-guide fixed over a printing-point, with a series of type-bars having pivot-shafts arranged at opposite sides of the same, with cranks at the end of the pivot-shafts, key-levers *i* having their inner ends over the said cranks and their outer ends provided with finger-keys, and the fulcrum-plate *f* intermediate to the ends of the key-levers, substantially as shown and described.

35. In a type-writer, the combination, with a journal-plate having converging sides, with a series of bearings extended across such sides, and a series of type-bars having pivot-shafts journaled in said bearings, with cranks *e* in a straight line upon the ends of the pivot-shafts along one side of the journal-plate, of the pivots 6 and 8 upon the ends of the journal-plate in line with the cranks, means to rock the journal-plate, and finger-keys with connections to the said cranks to oscillate the pivot-shafts, whereby the relation of the connections to the cranks is maintained when the journal-plate is rocked on the said pivots.

36. In a type-writer, the combination, with a journal-plate having a series of bearings disposed transversely across the same with a series of type-bars of gradually-increasing lengths having pivot-shafts fitted in the said bearings and each having a transverse head bearing a plurality of characters, cranks and connections for actuating the pivot-shafts, an alinement-guide suitably arranged at a printing-point to receive the heads of all of the type-bars, a swivel-box at one end of the journal-plate with means for shifting the journal-plate upon such swivel-box, and the alinement-guide and the heads of the type-bars being curved concentric with the said

swivel-box, whereby the heads are alined in the various shifted positions of the journal-plate, substantially as herein set forth.

37. In the type-writer, the combination, 5 with the type-bars herein described having at one end a head extended transversely to the bar, such head curved in the direction of its extension from the bar and having upon one side a plurality of type-faces inclined to 10 one another and disposed in the same relation to the said curve, of means for twisting the bar to bring the several type-faces successively into the same plane, and means for swinging the type-bars to bring the several 15 type-faces at pleasure to the same printing-point.

38. The type-bar herein described, having at one end a head extended transversely to the bar, such head curved in the direction of 20 its extension from the bar and having upon one side a plurality of type-faces inclined to one another and disposed in the same relation to the said curve, in order that either of the said type-faces may be brought successively 25 parallel with the same printing-plane when the bar is twisted, and means for supporting the bar, to permit it to be twisted or laterally rocked and swung as herein described, to bring the several type-faces at pleasure to the 30 same printing-point.

39. In a type-writing machine, a nest of type-bars of graduated lengths and pivoted at correspondingly-graduated distances from the printing-center and so that they may 35 swing past one another, said type-bars mounted in a row which radiates from the printing-center, and their pivots lying in converging relation such that all of the type-bars when in printing positions extend radially 40 from the printing-center to their pivots.

40. In a type-writing machine, a nest of type-bars each carrying a plurality of types, said type-bars being of graduated lengths and pivoted at correspondingly-graduated 45 distances from the printing-center and so that they may swing past one another, the types extending angularly from the free ends of the bars but close thereto, said type-bars mounted in a row which radiates from the 50 printing-center, each type-bar overlapping the next, and their pivots lying in converging relation so as to enable all the types to strike at the printing-center.

41. In a type-writing machine, a nest of 55 single-arm type-bars each carrying a plurality of types, said type-bars being of graduated lengths and pivoted at correspondingly-graduated distances from the printing-center, the types extending angularly from the 60 free ends of the bars, both types and bars being arranged in echelon, the bars being in a row which radiates from the printing-center, and so pivoted that all of the types may strike at the printing-center.

65 42. In a type-writing machine, a system of

type-bars consisting of two rows radiating from opposite sides of the printing-point, the type-bars in each row being of graduated lengths and mounted at correspondingly-graduated distances from the printing-center, 70 each bar provided with a multiple type which extends angularly from the end of the bar, both types and bars being arranged in echelon and the bars being mounted with their pivots in converging relation, so that all of the 75 types may strike at the printing-center.

43. A book type-writer comprising a flat platen, a system of single-arm type-bars mounted to strike down upon said platen and consisting of two rows of bars which radiate 80 from opposite sides of the printing-center, said type-bars being of gradually-increasing lengths and mounted at corresponding distances from the printing-center, and being arranged in echelon, with their pivots converging so that all the types may strike at 85 the printing-center, key-bearing levers extending forwardly from said type-bars, above said platen, and links connecting said type-bars to said levers.

44. A book type-writer comprising a flat platen, a system of single-arm type-bars mounted to strike down upon said platen and consisting of two rows of bars which radiate 90 rearwardly and outwardly from opposite sides of the printing-center, said type-bars being of gradually-increasing lengths and mounted at corresponding distances from the printing-center, and being arranged in echelon and mounted upon rearwardly-converging 95 rock-shafts of gradually-increasing lengths from the center to the sides of the system, crank-arins upon the forward ends of the rock-shafts, links extending upwardly from the crank-arins, a system of keys, and two 100 sets of levers, said sets diverging rearwardly from said keys and fulcrumed between their ends and connected at their rear ends to said links.

45. In a type-writing machine, the combination of a system of type-bars consisting of two rows radiating from opposite sides of the printing-point, the type-bars in each row being of graduated lengths and mounted at correspondingly-graduated distances from 110 the printing-center, each bar being provided with a multiple type which extends angularly from the end of the bar, both types and bars being arranged in echelon, and the bars being mounted with their pivots in converging relation, so that all of the types may strike at the printing-center, key-bearing levers connected to said type-bars, and means for shifting the type-bar system independently of the key-levers, to enable the different 115 types to print.

46. In a top-strike writing-machine, the combination with a system of type-bars consisting of two rows radiating from opposite 120 sides of the printing-center, the type-bars in 125

- each row being of graduated lengths and mounted at correspondingly-graduated distances from the printing-center, of a system of levers mounted above the type-bar pivots and connected at their rear ends to the type-bars and extending forwardly therefrom, keys carried by said levers, and means for shifting the type-bars independently of the key-levers, to enable different types to print.
47. In a top-strike writing-machine, the combination of a system of type-bars consisting of two rows radiating from opposite sides of the printing-center, the type-bars in each row being of graduated lengths and mounted at correspondingly-graduated distances from the printing-center, a system of key-bearing levers extending forwardly from the type-bars, links depending from the rear ends of the levers and connected to the type-bars, and means for shifting the type-bar system to enable different types to print, independently of the key-lever system.
48. In a top-strike writing-machine, the combination with a main frame, of a system of type-bars consisting of two rows radiating from opposite sides of the printing-center, the type-bars in each row being of graduated lengths and mounted at correspondingly-graduated distances from the printing-center, means for shifting the system of type-bars upon said frame, to enable different types to print, a system of key-bearing levers of the first order extending forwardly from the type-bars and fulcrumed directly upon said main frame, and links depending from the rear ends of the key-levers and connected to the type-bars and vibrating idly about their points of attachment to the key-levers during the shifting movements of the type-bar system.
49. In a top-strike writing-machine, the combination with a system of type-bars consisting of two rows radiating from opposite sides of the printing-center, the type-bars in each row being of graduated lengths and mounted at correspondingly-graduated distances from the printing-center, of a system of keys, two sets of levers bearing said keys, said sets diverging rearwardly from the key-board to said type-bars, and at their rear ends operatively associated with the latter, a shift-key, and means operable by said shift-key for shifting both of said rows of type-bars while said key-levers remain stationary.
50. In a top-strike writing-machine, the combination with a system of type-bars consisting of two rows radiating rearwardly from opposite sides of the printing-center, the type-bars in each row being of graduated lengths and mounted at correspondingly-graduated distances from the printing-center, said type-bars being mounted upon forwardly-extending rock-shafts of gradually-increasing lengths, crank-arms upon said rock-shafts, links extending upwardly from

said crank-arms, key-levers mounted upon the frame of the machine and connected to said links, and supporting means wherein said rock-shafts are mounted; said supporting means being shiftable while said key-levers remain stationary, and the links vibrating idly during the shifting movements.

51. In a type-writing machine, the combination with a platen, of a system of type-bars pivoted to strike upon the top of the platen, the type-bars being mounted in two rows which radiate from opposite sides of the printing-point, each type-bar having fixed thereon a plurality of types extending angularly from the type-bar and having their faces inclined to each other, a system of key-bearing levers operatively associated with the type-bars, and means for rocking the type-bars while said levers remain stationary.

52. In a top-strike writing-machine, the combination with a system of type-bars consisting of two rows radiating from opposite sides of the printing-center, the type-bars in each row being of graduated lengths and mounted at correspondingly-graduated distances from the printing-center, each type-bar having fixed thereon a plurality of types with their faces inclined to each other, of a system of levers mounted above the type-bar pivots and connected at their rear ends to the type-bars and extending forwardly therefrom, keys carried by said levers, and means for rocking the type-bar system forwardly independently of said levers, for enabling different types to print.

53. In a top-strike writing-machine, the combination of a system of type-bars consisting of two rows radiating from opposite sides of the printing-center, the type-bars in each row being of graduated lengths and mounted at correspondingly-graduated distances from the printing-point, each type-bar having fixed thereon a plurality of types with their faces inclined to each other, a system of key-bearing levers extending forwardly from the type-bars, links connecting the rear ends of the levers to the type-bars, and means for rocking the type-bar system while the key-levers remain stationary.

54. In a top-strike writing-machine, the combination with a main frame, of a system of type-bars consisting of two rows radiating from opposite sides of the printing-center, the type-bars in each row being of graduated lengths and mounted at correspondingly-graduated distances from the printing-center, supporting means whereon said type-bars are pivoted, said supporting means being mounted upon said main frame for a rocking movement to enable different types to print, a system of key-bearing levers fulcrumed directly upon said main frame and extending forwardly from the type-bars, and connections extending directly from the rear

ends of the key-levers to said type-bars and mounted to vibrate idly about their points of attachment to the key-levers during the shifting movements of the type-bar system.

- 5 55. In a top-strike writing-machine, the combination with a system of type-bars consisting of two rows radiating from opposite sides of the printing-center, the type-bars in each row being of graduated lengths and mounted at correspondingly-graduated distances from the printing-center, each type-bar having a plurality of types fixed angularly thereon with the type-faces inclined to each other, a system of keys, two sets of levers bearing said keys, said sets diverging rearwardly from the keyboard to said type-bars, and at their rear ends operatively associated with the latter, and means upon which said system of type-bars may rock independently of said levers, for enabling different types to print.

56. A book type-writer comprising a flat platen, a system of type-bars mounted to strike down upon said platen and consisting of two rows radiating from opposite sides of the printing-center, the type-bars in each row being of graduated lengths and mounted at correspondingly-graduated distances from the printing-center, each type-bar having a plurality of types whose faces are inclined to each other, key-bearing levers mounted above said platen and operatively associated with the type-bars, and means for rocking the type-bar system while the key-levers remain stationary, for enabling different types to print.

57. A book type-writer comprising a flat platen, a system of type-bars mounted to strike down upon said platen and consisting of two rows radiating from opposite sides of the printing-center, the type-bars in each row being of graduated lengths and mounted at correspondingly-graduated distances from the printing-center, each type-bar having a plurality of types whose faces are inclined to each other, a system of keys, two sets of levers bearing said keys, said sets diverging rearwardly therefrom, and mounted above said platen, connections from said key-levers to said type-bars, and means for rocking the system of type-bars independently of the key-levers.

58. A book type-writer comprising a flat platen, a system of type-bars mounted to strike down upon said platen and consisting of two rows radiating from opposite sides of the printing-center, the type-bars in each row being of graduated lengths and mounted at correspondingly-graduated distances from the printing-center, each type-bar having a plurality of types whose faces are inclined to each other, a system of key-levers fulcrumed between their ends above said platen and bearing keys at their forward ends, links depending from the rear ends of said levers and

connected to said type-bars, and means for rocking the type-bar system independently of said levers; the construction being such that during the rocking of the type-bars said links vibrate idly about their points of connection to said key-levers.

59. In a type-writing machine, the combination of a nest of type-bars of graduated lengths and pivoted at correspondingly-graduated distances from the printing-center and so that they may swing past one another, said type-bars mounted in a row which radiates from the printing-center and each having fixed thereon at an angle thereto a plurality of types whose faces are inclined to each other, the type-bar pivots lying in converging relation such that all of the type-bars when in printing positions extend radially from the printing-center to their pivots, and means for rocking said nest of type-bars to enable different types to print.

60. In a type-writing machine, the combination of a nest of type-bars, of graduated lengths and pivoted at correspondingly-graduated distances from the printing-center and so that they may swing past one another, each type-bar being provided with a plurality of types fixed thereon angularly thereto with the type-faces inclined to each other, said type-bars mounted in a row which radiates from the printing-center, each type-bar overlapping the next, and their pivots lying in converging relation so as to enable all the types to strike at the printing-center, levers connected to said type-bars, keys for said levers, and means for rocking the type-bars independently of the levers, to enable the different types to print.

61. In a book type-writer, the combination with a flat platen, of a nest of single-arm type-bars mounted to strike down upon the platen, said type-bars being of graduated lengths and mounted at correspondingly-graduated distances from the printing-center, and each provided with a plurality of types extending angularly from the bar, the type-faces being inclined to each other, both types and bars being arranged in echelon, the bars being in a row which radiates from the printing-center, and so pivoted that all of the types may strike at the printing-center, a set of key-levers also mounted above said platen and connected to the type-bars, and means for rocking said type-bars while the key-levers are stationary.

62. In a book type-writer, the combination of a flat platen, a system of type-bars consisting of two rows radiating from opposite sides of the printing-center, the type-bars in each row being of graduated lengths and mounted above said platen at correspondingly-graduated distances from the printing-center, each bar being provided with a plurality of types extending angularly therefrom and with their faces inclined to each other,

- both types and bars being arranged in echelon, and the bars being mounted with their pivots in converging relation, so that all of the types may strike at the printing-center, a system of key-bearing levers mounted above said platen, links connecting said levers to said type-bars, and means for rocking the type-bar system while the levers remain stationary.
63. In a book type-writer, the combination with a system of type-bars consisting of two rows radiating rearwardly from opposite sides of the printing-center, the type-bars in each row being of graduated lengths and mounted above said platen at correspondingly-graduated distances from the printing-center, each type-bar having fixed thereon a plurality of types angularly thereto with their faces inclined to each other, and said type-bars being mounted upon forwardly-extending rock-shafts of gradually-increasing lengths, crank-arms upon said rock-shafts, links extending upwardly from said crank-arms, a system of keys, two sets of levers bearing said keys and diverging rearwardly therefrom above said platen and connected at their rear ends to said links, and means for rocking said system of type-bars independently of said levers.
64. In a type-writing machine, the combination of two rows of type-bars radiating from opposite sides of the printing-center, each type-bar having a plurality of types thereon with their faces inclined to each other, a rocking frame for each row of type-bars, the latter being pivoted upon said frames, and a key-controlled rock-shaft connecting said frames to cause them to rock together.
65. In a type-writing machine, the combination of two rows of type-bars radiating from opposite sides of the printing-center, each type-bar having a plurality of types thereon with their faces inclined to each other, a pair of supporting-frames one for each row of type-bars, each frame being supported at its outer end for universal pivotal motion and at its inner end for a tilting movement and also a movement transverse to the line of writing, a key-controlled rock-shaft controlling both of said frames for rocking them at their outer ends while both tilting and moving them transversely at their inner ends.
66. In a type-writing machine, the combination of two rows of type-bars radiating from opposite sides of the printing-center, each type-bar having a plurality of types thereon with their faces inclined to each other, supporting means whereon said type-bars are pivoted, and key-controlled means for imparting to said supporting means both a tilting movement and a movement transverse to the line of writing for enabling the different types to print.
67. In a type-writing machine, the combination of a system of type-bars, each having a plurality of types thereon with their faces inclined to each other, supporting means whereon said type-bars are pivoted, and key-controlled means for simultaneously 70 tilting and moving said supporting means transversely to the line of writing for enabling the different types to print.
68. In a type-writing machine, the combination of a system of type-bars, each having a plurality of types thereon with their faces inclined to each other, supporting means whereon said type-bars are pivoted, key-controlled means for both tilting and moving said supporting means transversely to the 80 line of writing for enabling the different types to print, stops for limiting such sliding movements, and stops for limiting such rocking movements.
69. The combination with a series of type-bars each having thereon a multiple type provided upon one side with a notch, of means for shifting the series of type-bars, a central type-guide having jaws to receive said types, one of said jaws having a projection to fit into said notch.
70. The combination with a series of type-bars each having thereon a multiple type provided upon one side with a notch, of a central type-guide having jaws to receive 95 said types, and means for effecting a relative case-shifting movement between said type-bars and said type-guide; one of said jaws having two projections, one fitting the type-bar notches at one shift, and the other fitting 100 them at the other shift.
71. The combination with a series of type-bars each having thereon a multiple type provided upon one side with a plurality of notches, of a central type-guide having jaws 105 to receive said types, one of said jaws having a projection which may fit either of said notches, and case-shifting mechanism.
72. The combination with a series of type-bars each having thereon a multiple type provided upon one side with a plurality of notches, of means for shifting the series of type-bars, a central type-guide having jaws to receive said types, one of said jaws having a plurality of projections for fitting 115 in said notches, and case-shifting mechanism.
73. In a type-writer, a system of type-bars having pivot-shafts and having type-faces inclined to one another, a frame for supporting said pivot-shafts in substantially parallel relation to one another, said type-bars being disposed in echelon, and means for moving said frame through an angle, said movement being independent of the 125 key-levers.
74. A type-bar action arranged to be operable upon a flat platen, comprising a frame having a plurality of pivot-shafts journaled therein and disposed in substan- 130

tially parallel relation, type-bars on said pivot-shafts arranged in echelon, and means for moving said frame through an angle, said movement being independent of the key-levers.

75. A type-bar action arranged to be operable upon a flat platen, comprising a frame having pivot-shafts therein in substantially horizontal relation, type-bars on said pivot-shafts arranged to strike downward toward the platen, and means for moving said frame

through an angle, the movement being independent of the key-levers.

In testimony whereof we have hereunto set our hands in the presence of two subscribing witnesses.

JOHN JAY HANNAHS.
